Specification of Letters Patent.

Patented Aug. 5, 1913.

Application filed July 3, 1911. Serial No. 636,775.

To all whom it may concern:

Be it known that I, JOHN C. FIDDYMENT, a citizen of the United States, residing at Baltimore, in the State of Maryland, have 5 invented certain new and useful Improvements in Presses, of which the following is a specification.

The present invention relates in general to presses of that type which are designed 10 to be employed for extracting the juices, liquid, or oil from any material containing the same, such as cotton seed, castor beans, nuts, fish, brewers' and packing house products and the like.

15 More particularly, the invention relates to novel and improved means adapted to be employed in connection with screw presses to overcome the tendency of the mass of material to rotate with the screw, and consequently to check any retrograde or creeping movement of the material backward toward the feeding end of the machine. Most materials that are to be pressed to extract oil or moisture are soft or semi-plastic and have 20 not a sufficient consistency to admit of the screw taking hold of the material and forcing it positively through the press with a uniform movement, and the object of the present invention is the provision of a novel 25 form of baffle which coöperates with the expressing screw to prevent the material from creeping back or turning with the screw in such a manner as to interfere with the proper compression of the material within 30 the press and to prevent the requisite amount of material being introduced at the feed 35 end of the press. In this connection, it may be mentioned that the amount of material introduced into the feed end of the press 40 governs the pressure therein, so that unless a proper amount of material is fed into the press the pressure required for a proper expressing action will not be present.

This improvement is intended to insure 45 the press getting the material in the proper amount, and to regulate the flow of the material through the pressure chamber from inlet to outlet in such a manner as to provide for and maintain a uniform expressing action 50 throughout the machine, and for this purpose a rotary baffle is provided which fits between adjacent convolutions of the spiral flange or thread of the expressing screw so as to prevent the material from creeping 55 around the screw and working its way backward, although there is little or no resistance

to the proper passage of the material through the press chamber from the feed end of the machine to the discharge end thereof.

In carrying out the invention, the same is necessarily susceptible to a wide range of structural modification without departing from the principle or sacrificing any of the advantages of the invention, although certain simple and practical embodiments of 60 the invention are illustrated in the accompanying drawings, in which:—

Figure 1 is a horizontal sectional view through a screw press constructed in accordance with the invention. Fig. 2 is a vertical 70 transverse sectional view through the same on the line 2—2 of Fig. 1. Fig. 3 is a detail view of a portion of the expressing screw and a modified form of the rotary baffle member. Fig. 4 is a transverse sectional 75 view through a portion of a screw press, showing a still further modification in which a screw is provided for feeding the material to the press and one of the rotary baffle members is mounted in coöperative relation 80 to the screw, and Fig. 5 is a detail view of the gearing between the screw and baffle member, in the modification shown by Fig. 4.

Corresponding and like parts are referred 85 to in the following description and indicated in all the views of the drawings by the same reference characters.

The invention is particularly designed to be employed in connection with a screw press 90 which may be of any conventional or approved construction.

As indicated upon the drawing, the numeral 1 designates the expressing screw which is arranged within the casing 2, the 95 ends of the screw being suitably journaled within the boxes 3. The screw is of the usual construction and is formed with a tapering body or drum 1^a which gradually increases in size from the receiving end of 100 the press chamber to the discharge or delivery end thereof, the said body being provided with a spiral flange or thread 1^b which fits closely within the cylindrical interior of the casing 2. As the screw is 105 revolved the flange 1^b is designed to act in the usual manner to move the material longitudinally through the press chamber, and owing to the fact that the space between the interior walls of the casing 2 and the 110 body 1^a of the screw gradually decreases toward the discharge end of the press, the

material will be subjected to a gradually increasing pressure as it is advanced through the machine, the maximum pressure being attained immediately before the discharge of the material. The casing 2 has a perforate construction to admit of the ready escape of the juices or oils extracted from the material as it is subjected to the squeezing action of the press. This casing 2 may 5 be conveniently constructed, as is shown upon the drawing, by assembling a series of rings 2^a in a spaced relation to each other so as to provide annular cracks or crevices at close intervals throughout the length of 10 the press for the escape of the liquid squeezed from the material.

Owing to the fact that most materials which are ordinarily subjected to the action of a press of this character are all of a soft 20 or semi-plastic nature, it has been found that there is a tendency for the material to turn with the screw or creep backward around the same so as to interfere with the proper action of the press. In order to ob- 25 viate this difficulty it is contemplated to employ a rotary tapered baffle member which will fit between various convolutions of the spiral flange so as to prevent retrograde or backward movement of the material. As 30 indicated on Fig. 1 there are two of these rotary baffles 4 arranged within a pocket 5 formed in one side of the casing 2, the said baffles being mounted upon a single shaft 6 which is parallel to the axis of the 35 screw 1. It will be observed that the said pocket 5 is an off-set of the casing which is formed by ring sections of double construction, as plainly shown in the sectional view, or Fig. 2 of the drawings, that is to 40 say, these particular ring sections have an upper ring member to accommodate the receiving end of the expressing screw, and a lower ring member communicating with the interior of the upper ring member and con- 45 forming to and accommodating the rotary baffle.

The inner end of the shaft 6 is journaled upon the casing at 7, while the outer end of the shaft is suitably journaled within a box 50 8 and is provided with a pinion 9 meshing with a similar pinion 10 carried by the screw 1. Each of the rotary baffles 4 has a spiral formation and fits closely between a pair of adjacent convolutions of the flange 1^b 55 of the expressing screw. When the expressing screw is turned, any suitable means being provided for this purpose, the shaft 6 and baffles 4 are simultaneously turned in an opposite direction, and the spiral formation 60 of the baffles causes them to conform to the movements of the screw so as to always provide a check or baffle to prevent the material within the press from creeping backward around the screw.

65 A slight modification is shown in Fig. 3

in which a single baffle member 4^a is employed, although the said baffle is considerably longer than in the previous instance and is formed with several spiral convolutions or flights which fit between corresponding convolutions of the flange 1^b of the expressing screw. Owing to the fact that as the material is moved through the press the juices or oil are gradually extracted therefrom, it becomes more solid or 70 dense as it approaches the discharge end of the press, so that ordinarily it is merely necessary to place the baffles at or near the feed end of the press, the expressing screw being capable of taking hold of the material 75 and properly pushing the same through the press after a portion of the liquid has been expelled therefrom. It is for this reason 80 that the rotary baffle members are shown in Fig. 1 as located adjacent the feed end of 85 the press.

A further modification of the invention is shown in Fig. 4 in which the feed opening 11 in a screw press 12 communicates with a tubular casing 13 having a screw member 90 14 mounted therein. The upper end of this screw member is provided with a pinion 15 which meshes with a smaller pinion 16 upon the upper end of a countershaft 17 which is arranged parallel to the axis of the screw 95 and is provided with a rotary spiral baffle member 18. This baffle member 18 is arranged within a pocket 19 in one side of the tubular casing 13 and engages the screw 14 in such a manner as to prevent the material 100 within the casing 13 revolving with the screw or creeping backward around the same. The upper end of the tubular casing 13 is formed with a feed opening 20 through 105 which material is designed to be fed to the screw, the said screw operating in the usual manner to take hold of the material and carry it down into the press 12.

From the foregoing description it will be 110 obvious that the essence of the invention resides in the provision of a baffle member which is designed to have a continuous rotary movement and engages the spiral flange of the expressing screw so that the material can be advanced through the casing by the 115 action of the screw without any material increased resistance thereof, although it is rendered impossible for the material to creep backward around the screw or have any retrograde movement. Under some conditions a series of these rotary baffle members may be utilized, as indicated upon Fig. 1, while under other conditions a single baffle member may be found sufficient, as indicated in Fig. 3, the number, size, and proportions 120 of the baffle member varying according to the nature of the material being operated upon or the individual ideas of the person using the press.

Having thus described the invention, what 130

I claim as new and desire to secure by Letters Patent, is:—

1. In a screw press, the combination with a perforate casing of uniform diameter throughout, an expressing screw extending through the casing from end to end and having a tapered body, and a rotary spiral baffle member arranged at one side of the screw at the material-receiving end of the 5 casing and having a geared connection with the screw, said baffle following the taper of the screw body and projecting between flights of the screw to the full depth of the space between said flights, the screw and the 10 baffle coöperating to compel the advance of the material through the press toward the outlet and preventing retrograde creeping of the material.
2. In a screw press, the combination of a 15 casing, an expressing screw conforming to the interior of the casing and operating in close relation thereto, the space between the spiral flanges of the screw, the body of the screw, and the casing, forming a spiral compression chamber the cross section of which is gradually reduced toward the discharge 20 end, one of the walls of said spiral compression chamber having openings for the escape of fluids expressed, and a rotary spiral baffle 25 of the material expressed, and a rotary spiral baffle

having its flanges extending into the spaces 30 between the screw flanges and filling said spaces in a part of the screw inclosed by the casing and closing the receiving end of the spiral compression chamber.

3. In a screw press, the combination of a 35 casing, an expressing screw conforming to the interior of the casing and operating in close relation thereto, the space between the spiral flanges of the screw, the body of the screw, and the casing, forming a spiral compression chamber, the cross section of which is gradually reduced toward the discharge 40 end, one of the walls of said spiral compression chamber having openings for the escape of fluids expressed, and a rotary spiral baffle 45 having its axis parallel with the axis of the screw and having its flanges extending into the spaces between the screw flanges and filling said spaces in a part of the expressing screw inclosed by the casing and closing 50 the receiving end of the spiral compression chamber.

In testimony whereof I hereunto affix my signature in the presence of two witnesses.

JOHN C. FIDDYMENT.
